UNITED STATES PATENT OFFICE.

NATHAN G. GURNEY, OF BALTIMORE, MARYLAND, ASSIGNOR OF ONE-HALF
TO FRANCIS CLARK, OF SAME PLACE.

PROCESS APPARATUS.

SPECIFICATION forming part of Letters Patent No. 296,285, dated April 1, 1884.

Application filed March 6, 1883. (No model.)

To all whom it may concern:

Be it known that I, NATHAN G. GURNEY, a citizen of the United States, residing at Baltimore, Maryland, have invented new and useful Improvements in Process Apparatus, of which the following is a specification.

My invention relates to a class of heating-kettles, known technically in the art as "process-kettles;" and the novelty consists in the construction and arrangement of parts, as will be more particularly hereinafter set forth, and specifically pointed out in the claims.

The object of the invention, in cooking and treating canned fruit, vegetables, fish, and other edibles, is to provide a kettle or vessel adapted to receive the cans to be treated, which vessel shall have steam-connections with a suitable generator, and means for automatically relieving the pressure when it reaches a determined point, means for preventing condensation of steam in such vessel, and of vaporizing any such condensation as may have occurred, and means for maintaining any desired degree of heat in the vessel after the steam-supply has been cut off; and to these ends the invention consists, essentially, in the mechanisms and combinations of mechanisms fully illustrated in the accompanying drawings, which form a part of this specification, and in which—

Figure 1 is a vertical transverse section, and Fig. 2 a vertical central section taken at right angles thereto. Fig. 3 is a sectional view, showing a modification.

Referring to the drawings, in which similar letters of reference indicate like parts in both the figures, A designates a horizontal tubular boiler of any approved and suitable construction and capacity, and A' a furnace for heating the same. Secured properly, by bolts or rivets, to make a steam-tight joint, to this boiler is a vertical cylinder, B, having open connection with the steam-space above the water-level in said boiler A. By proper flanges upon a cylindrical vessel, C, said vessel is supported or suspended or otherwise secured within the cylinder B, and this vessel is adapted to receive and hold the cans while being treated. The vessel C is of such smaller diameter than the cylinder B as to form an annular space,

M, as shown, which space connects with the steam-space in the boiler A.

The flanges by means of which the cylinders B and C are connected are so arranged and constructed as to form a steam-tight joint, 55 and also to form a seat for the bearings of a removable cover, C', which is secured to its said seat by bolts e, proper packing being interposed to form a steam-tight joint at this point. The means for holding this cover to its seat are such as to allow the ready removal of the cover for the insertion of the cans.

A horizontal pipe, E, is connected with the bottom of the vessel C, and provided with a vertical branch, E', the upper end of which 65 is connected with the upper portion of the cylinder B, to establish communication between the annular space M and the interior of the vessel C, at the bottom thereof, such communication being controlled by a valve, F, in 70 the vertical branch E. At a point between this vertical branch and the outer end of the pipe E is arranged a blow-off cock, G. When the cans are in proper position within the vessel C and the cock F is opened, the steam 75 will pass from the annular space M through the vertical branch E' and pipe E into the bottom of the said vessel.

D indicates a pipe leading from the interior of the vessel C to a point outside the cylinder 80 B, to which a safety-valve, D', is attached. As different degrees of pressure may be required within the vessel C, I provide an adjusting device, D", which may be set at any predetermined point, so that it will resist the 85 pressure up to such predetermined point, when the valve will open and relieve the vessel C. A similar device, I, is attached to the pipe E, near its connection i with the steam-space M, and a pipe, H, connected with such space M, 90 carries a steam-gage, h, to denote the pressure in the said space and boiler.

When the proper pressure of steam in the vessel C is attained, such live steam having been admitted from the boiler A through the 95 pipe E, the valve F is closed. The amount of heat from the boiler is sufficient to vaporize into steam any water of condensation in the bottom of the vessel C, and to prevent further condensation.

To properly distribute the steam injected through the pipe E among the several cans, I provide a deflecting-plate, J, which may be perforated if desired, which plate is located 5 within the vessel C, slightly above its bottom, and arranged to cover the inlet-orifice of said pipe.

It will be observed that the apparatus will need but very little attention in service, as the 10 safety features prevent accident, the principal care being to remove the treated cans, place in the vessel C a new lot of cans to be treated, turn the valve F until a proper amount of steam has been injected, then shut off the 15 valve F, the other steps in the process being automatic.

When for any reason it becomes necessary to blow off the vessel C, to remove sediment, for instance, the valve G may be opened for 20 that purpose.

Modifications in details of construction may be made without departing from the principle or sacrificing the advantages of my invention, the essential features of which will be readily 25 understood from the foregoing description, taken in connection with the drawings. For instance, the vessel C may be also secured to the cylinder B at the lower junction with the boiler, or at any intermediate point, by a per- 30 forated annular metal ring; and in case the aperture formed by the connection with the cylinder and boiler should seriously weaken that part of the boiler, both the cylinders B and C may be bolted to the boiler, and the 35 portion of the said boiler between the junctures of the cylinders may be perforated, the other features remaining substantially as shown.

Having thus described my invention, what I claim is—

1. In a processing apparatus, a jacketed 40 kettle having a connection with a steam-generator and surrounded by a steam-space having open connection with said steam-generator, and means for automatically relieving pressure within said kettle when a predetermined 45 point of pressure has been reached, as set forth.

2. In a process apparatus, the combination, with a steam-boiler, of a vertical cylinder having its lower open end in direct communication with the steam-space of the boiler, and secured to the boiler-casing by a steam-tight 50 joint, a can receiving and supporting vessel secured within the cylinder by flanges, to form a seat for the removable cover, and a steam-supply pipe for delivering steam into the vessel, upon the cans therein, substantially as described.

3. In a processing apparatus, and in combination with the boiler A, jacketed kettle and 60 cover, as described, a steam-pipe, E, connecting with the interior of the vessel or kettle, and having a branch, E', connecting with the steam-space exterior to the said kettle, and with proper valves, as and for the purposes 65 set forth.

In testimony whereof I have hereunto set my hand in the presence of two subscribing witnesses.

NATHAN G. GURNEY.
